Filed Aug. 11, 1975, Ser. No. 603,274

Term of patent 14 years

Int. Cl. D15—99

U.S. CL. D15—149

FIG. 1 is a left side elevational view of a machine for rotating reel type mowers to lap in blades or the like showing my new design, a portion of the electrical power cord being omitted for clarity of illustration;

FIG. 2 is a front elevational view thereof;

FIG. 3 is a top plan view thereof;

FIG. 4 is a rear elevational view taken along line 4—4 of FIG. 1;

FIG. 5 is a right side view taken along line 5—5 of FIG. 4 with an end of the handle broken away for clarity of illustration; and

FIG. 6 is a bottom view thereof, with one of the carriage bolts broken away for clarity of illustration.

I claim:

The ornamental design for a machine for rotating reel type mowers to lap in blades or the like, substantially as shown and described.
